UNITED STATES PATENT OFFICE.

JOHN S. CAMERON, OF BOSTON, MASSACHUSETTS, ASSIGNOR TO WALTER T. STALL AND CHARLES H. DEAN, COPARTNERS DOING BUSINESS AS STALL & DEAN MANUFACTURING COMPANY, AT BROCKTON, MASSACHUSETTS.

BALL-PLAYER'S GLOVE.

1,072,697.

Specification of Letters Patent.

Patented Sept. 9, 1913.

Application filed July 18, 1912. Serial No. 710,139.

To all whom it may concern:

Be it known that I, JOHN S. CAMERON, a citizen of the United States, and resident of Boston, in the county of Suffolk and 5 State of Massachusetts, have invented certain new and useful Improvements in Ball-Players' Gloves, of which the following is a specification.

This invention relates to gloves or mitts 10 used by ball players to protect the hand in catching a ball, and has for its object to provide such a glove with means for assisting the fingers of the hand, on which the glove is worn, to grasp the ball more quickly 15 after the latter strikes the palm of the hand, and also for protecting the fingers to some extent from injury when struck by the ball.

With these objects in view, the invention 20 consists, broadly, in so incorporating weights in the fingers of the glove that they occupy locations at the front and tips of the fingers of the hand on which the glove is worn; and more specifically, in the particular manner in which the weights are built 25 into the glove.

In the accompanying drawings wherein 30 I have drawn the preferred embodiment of my invention,—Figure 1 represents a front view of the glove, Fig. 2 is a sectional view of one of the fingers of the glove on line 2—2 of Fig. 1, Fig. 3 is a perspective view of one of the weights removed from the glove.

Like reference characters represent the 35 same parts in all the views.

The glove in which the present invention 40 is embodied may be of any character, and in the embodiment here shown is digitated to provide distinct pockets for the digits of the player's hand. These digital divisions 45 which for convenience I will term the fingers of the glove are designated by the letter *a*, and the part which extends over the palm of the wearer's hand is designated *b*. In certain of the fingers, it may be one or more, I provide a weight or weights *c* indicated by dotted lines in Fig. 1, and more fully shown in Fig. 2.

In the embodiment of the invention here 50 illustrated the weights are applied in all five fingers of the glove, although the essence of the invention would not be altered if they were omitted from some. The manner and mode of building the weights in

the glove is shown in Fig. 2, which although 55 specifically representing the middle finger is also a representation of all the fingers in which the weights are incorporated. The glove has an inner flexible covering or lining *d* which comes next to the skin of the 60 wearer's hand and is made conveniently of leather, and an outer flexible covering *e* also preferably made of leather. These coverings are cut and sewn together in the manner usual with gloves of this character. 65 A padding *f* is secured to the lining at the front of the glove. This pad and the outer covering extend over the palm and fingers of the glove. The weight *c* is secured between the padding and outer cover at the 70 tip end of the finger.

The mode of attaching the weight is a feature of this invention and is as follows: The weight, which is preferably of metal, is inclosed in a sort of sack made of a strip 75 of material *g* which is doubled over the weight and the parts of which are stitched together around the edges of the latter. This sack, which is conveniently of leather, is sewed to the lining and padding, a part 80 of the stitching for this purpose being shown at *h*. One end of the piece from which the sack is made extends along the finger beyond the weight as shown at *g'* to make the attachment of the weight additionally secure. The mode of attachment of 85 one weight above described is followed in case of all weights.

One of the weights is shown in detail in Fig. 3. It is concave on the side *c'* which is 90 faced toward the back of the glove, in order that it may fit the wearer's finger, and on the front side is convex to enable it to lie smoothly in the outer covering which is ordinarily convex. The substance of which 95 the weight is made is preferably lead, whereby the weights may be sufficiently heavy without being too bulky.

The effect of the weights is to give the player greater speed in grasping the ball, 100 thus reducing the chance of the ball bounding out of his grasp after it has struck his hand. The part of the glove extending over the wearer's palm constitutes a ball-receiving portion or member which receives the 10 impact of the flying ball and is forced backward when struck by the ball. Those parts of the outer covering which extend from the

palm portion to the ends of the wearer's fingers and to which the weights are secured are connectors between the ball-receiving portion and the weights, and draw 5 the weights forwardly and inwardly when the ball-receiving portion is thus suddenly pushed backward. The inertia and momentum of the weights as moved cause force to be applied to the player's fingers through 10 the backs of the finger pockets at their tips, assisting the fingers to close quickly around the ball. In many instances the impetus given to the player's fingers in this manner is enough to save the instant of time in 15 which the ball might bound out of his grasp, and enable him to hold the ball when otherwise he would have dropped it.

Another purpose which the weights serve 20 is to protect the fingers of the wearer against harm when the ball strikes the finger tips instead of the palm. The weights being formed as hereinbefore described lie somewhat over the tips of the fingers and form a metallic armor, which in the case of 25 a ball striking the finger tips takes the first shock of the impact and softens the blow.

Where I have used the terms "front" and "back", or "rear", I have intended them to be used in the same sense in which 30 they are ordinarily used in reference to a person's hand, the front of the hand or fingers being the palm side, and the back being, of course, the opposite side.

I desire further to state that although I 35 have described my invention as applied to a digitated glove, yet I do not thereby intend to limit the invention, or to imply that the

scope of the invention is not sufficiently broad to cover a mitt without digits, but provided with a weight or weights at locations near the positions occupied by the finger tips of the wearer. I have used the words "hand protector" in certain of the appended claims to signify any article in the nature of a glove, whether having finger 40 divisions or not, which serves the purpose of a glove or mitt in softening the impact of a ball and protecting the player's hand. 45

I claim:

1. A ball-player's hand protector having a 50 portion arranged to receive the impact of a flying ball, finger pockets connected to said portion, and metallic pieces of appreciable weight secured within the ends of certain of such pockets.

2. A ball-player's hand protector having finger pockets, and metallic pieces of appreciable weight secured within the ends of certain of such pockets only at the front thereof said pieces being concave on the rear 55 sides to fit the tips of the wearer's fingers.

3. A ball-player's hand protector comprising a hand covering and a lining therefor, a leather sack secured to the lining, and a weight inclosed in said sack, the location of 60 the sack being such that the weight lies near the tip of a finger on the hand on which the glove is worn.

In testimony whereof I have affixed my signature, in presence of two witnesses.

JOHN S. CAMERON.
